SOAP DISH

John Kirkbride, Detroit, Mich.

Application January 18, 1946, Serial No. 642,052

1 Claim. (Cl. 45—28)

1

This invention relates to soap dishes and more particularly to a soap dish that will elevate the soap and separate the soap from the usual water and moisture carried thereby after being used.

It is a known fact that the water and moisture retained on the soap after use thereof will adhere to the soap and cause the melting thereof, thereby decreasing the life of the soap and its usefulness.

An object of this invention therefore is to provide a soap dish that will drain the water from the soap, is simple in construction, efficient in operation, durable in use and inexpensive to manufacture.

With the above and other objects and advantages in view the invention consists of the details of construction, arrangement and combination of parts more fully hereinafter described, claimed and illustrated in the accompanying drawings in which:

Figure 1 is a perspective view of an embodiment of the invention.

Figure 2 is a sectional view on the line 2—2 of Figure 1.

Figure 3 are perspective views of the removable soap supporting bar, and

Figure 4 is a detailed fragmentary view of the supporting bar and elevated end of the device.

Referring more in detail to the drawing the reference numeral 10 designates the soap dish having straight marginal side walls 12, curved endwalls 14 and a straight bottom 16, the walls are perpendicular to the bottom thereof and form the straight upper marginal rim 18.

Formed integral with one end of the dish and joining the side bottom and end walls adjacent the upper marginal rim 18 is the inclined raised platform 20 which permits drainage of soap placed in the dish into the well 22 formed at the opposite end of the dish by the front wall 24 of the platform 20.

Formed at right angles to the platform 20 are the upstanding square shaped pegs or lugs 26 which having straight upper ends 28 contact the soap at an angle thereby presenting a limited supporting area.

Positioned immediately above the well 22 and formed on the side walls adjacent the upper rim of the dish are the opposed parallel U-shaped supporting ledges 30 which are adapted to removably receive the supporting bar 32, the upper upright of the ledges are inclined at 34 to permit

easy insertion of the bar and the ledges are at an inclined relation with the upper marginal rim.

The bar 32 is rectangular in cross section and is provided with the upstanding square shaped lugs or pegs 36 thus the pegs 26 and 36 are at inclined relation to the soap when it is laid thereon.

There has thus been provided a soap dish which will effectively drain all water and moisture from the soap since the soap is supported in an elevated position and will facilitate grasping of the soap by reason of the few points of contact between the supporting means for the soap and the dish.

It is believed the invention and its use will be apparent to those skilled in the art and it is to be understood that changes may be made in the details of construction arrangement and combinations of parts without departing from the spirit of the invention and the scope of the appended claim.

Having thus described the invention what is claimed as new and desired to be secured by Letters Patent is:

A device of the character described, comprising a soap dish having a bottom, straight side walls and curved end walls perpendicular to said bottom, a raised platform in said dish at one end thereof, the top surface of said platform being inclined downwardly toward the bottom of the dish from the upper end of one of the curved walls thereof relatively spaced upstanding square shaped lugs on said platform adjacent the forward end thereof for supporting one end of a cake of soap, a well formed in the dish forwardly of said raised platform, opposed parallel U-shaped supporting ledges formed on the side walls of said dish on the inner sides thereof above the well in inclined relation thereto and a removable bar at the other end thereof in said ledges having square shaped lugs formed thereon for supporting the opposite end of said soap.

JOHN KIRKBRIDE.
